REARVIEW MIRROR

Francesco Collura, New York, N. Y., assignor to The Roberk Company, Norwalk, Conn., a corporation of Connecticut

Application February 14, 1956, Serial No. 40,166

Term of patent 7 years

(Cl. D14—6)

Figure 1 is a side elevational view of a rearview mirror, showing my new design.

Fig. 2 is a top plan view of the arm and base with the mirror housing removed for clarity.

Fig. 3 is a rear view of the full line portion of the drawing.

The dominant features of my design reside in the portions shown in full lines.

I claim:

The ornamental design for a rearview mirror, as shown and described.
